RIVET-SETTING MACHINE.

1,185,776.

Specification of Letters Patent. Patented June 6, 1916.

Application filed June 25, 1915. Serial No. 36,371.

To all whom it may concern:

Be it known that I, JAMES W. COOMBS, a citizen of the United States, and resident of Philadelphia, county of Philadelphia, and State of Pennsylvania, have invented an Improvement in Rivet-Setting Machines, of which the following description, in connection with the accompanying drawings, is a specification, like letters on the drawings 10 representing like parts.

The invention to be hereinafter described relates to rivet setting machines, and more particularly to that type of such machines for riveting hand bags, suit cases, and the 15 like.

In machines of this general character, the work to be riveted is sustained by a rigid work support or post, while the rivet setting force is applied by a plunger toward 20 the work support or post to cause the rivet to first pass through the work and then be set. The character of the rivet setting force is such that the work support or post must be rigidly held to withstand the constantly 25 recurring blows to which it is subjected, and to this end it has heretofore been proposed to connect the work support or post directly with the machine frame by bolts or other securing means, or by casting a portion of

30 the work support directly with the machine frame or standard. The shorter the work support or post, the more effectually will it withstand the rivet setting blows with a constant increase in the life of the machine.

35 Certain kinds of work, however, require a long work supporting post or spindle, and this is particularly so in riveting the bottoms, corners, etc., of deep hand-bags, and the like. Other kinds of work do not necess-

40 sitate the use of such a long work supporting post or spindle, as in riveting ordinary suit cases, or shallow hand bags, and where this work is to be done advantage has heretofore been taken of the fact that a work 45 supporting post or spindle of less length might be employed, and a second machine having such shorter or medium length post or spindle has been provided. In some other classes of work, such as securing the

50 hinges, locks, etc., to hand bags and suit cases, only a very short work supporting post or spindle is necessary, and since the life of the machine is to an extent dependent upon the length of the work-supporting post

or spindle and its consequent rigidity and 55 ability to stand up under the riveting blows, a third machine has generally been provided with a short post or spindle. In the factory equipment for setting rivets, therefore, three machines have usually been provided, each with a work-supporting post 60 or spindle of appropriate length for the special work to be done by that machine.

One of the purposes of the present invention is to provide a machine of the general 65 character mentioned with a plurality of work-supporting posts or spindles of appropriate length required for the work of setting rivets in hand-bags, trunks, suit cases, and the like, and so combine such plurality of posts or spindles in a single machine that any one of them may be placed in operative position relative to the rivet-setting mechanism.

Another important feature of the present 75 invention consists in associating the various spindles or posts on a sleeve, the character and length of which are such that each spindle or post may be as rigidly supported for the action of the rivet setting mechanism 80 as if secured or bolted to the machine frame itself.

Still another feature of the invention consists in securing each of the several posts or spindles of varying length as required by 85 the work to a single sleeve having extended bearings on the machine column and capable of rotary movement thereon to bring any one of the posts or spindles into operative 90 position according to the character of work to be done.

Other features of the invention will hereinafter be described in connection with the accompanying drawings, showing a good practical embodiment of the invention in 95 its entirety.

In the drawings: Figure 1 is a side elevation of a rivet setting machine, some of the parts being broken away, embodying the present invention; Fig. 2 is a front elevation of the machine shown in Fig. 1; Fig. 3 is a section on line 3-3, Fig. 1; and Fig. 4 is a sectional detail showing a portion of the rivet setting mechanism.

The machine frame may be of any usual 105 or desired form appropriate for the herein-after-described purposes, and as shown, comprises a base portion 1 from which rises the

machine standard 2 surmounted by the goose-neck 3 for supporting the rivet setting mechanism. The front portion of the goose-neck 3 is provided with a seat 4 upon which 5 is adapted to be secured the block 5 by any suitable means such as the screws 6. The block 5 is designed to support the main working parts of the rivet setting mechanism, the construction being such that by 10 simply removing the screws 6, or other securing means, the block 5 may be readily removed from the machine frame and with it the rivet setting mechanism. This is often desirable for purposes of repair, or change 15 in the operative condition of parts or for the substitution of different forms of rivet setting head.

The block 5 has extending upward therefrom the chute 7 which communicates with a 20 suitable rotating member 8 to which the rivets may be supplied through the delivering trough 9. The shaft 10 carries within the hopper 8, suitable rotating means for agitating the rivets, but as these form no 25 essential part of the present invention, description thereof is unnecessary. Secured to the shaft 10 is a ratchet wheel 11 adapted to be actuated for rotating the agitating means within the hopper by the pawl 12 mounted 30 on the arm 13 which is itself pivotally secured by a detachable pin 14 to the main operating arm 15 of the rivet setting mechanism. The arm 13 is preferably slotted, as at 16, to embrace the shaft 10 and be guided 35 thereby. Mounted for reciprocating movement in the block 5 is the rivet setting plunger 17 which is connected at 18 to the stirrup or link 19 secured to the end of the operating arm 15, substantially as indicated 40 in Figs. 1 and 4. The operating arm 15 is pivotally mounted on brackets rising from the goose-neck 3, as at 20, the construction being such that upon movement of the operating arm 15 through the means hereinafter 45 to be described, the rivet setting plunger 17 may be reciprocated in the block 5 and the agitating means in the hopper 8 may be suitably rotated.

As the rivets are fed downward in the 50 chute 7, they are to be presented singly to the rivet holder which, in the present form of the invention, comprises the head 21, Fig. 2, carried by the arm 22 mounted for reciprocating movement in the block 5 and 55 normally held in raised position by a spring 23. The arm 22 has connected therewith an adjusting screw 24 whereby to limit the downward movement of the holder when the latter is depressed, as usual in this class of 60 machines, by the descending movement of the rivet setting plunger 17.

In order that the rivets may be properly delivered to the holder 21 one at a time, the chute 7 is provided with a cut-off or slide 25, 65 Fig. 4, which is mounted for movement

transversely of the chute and is provided with an opening, as usual for the passage of a rivet therethrough from a position above to a position below the said cut-off or slide. The cut-off or slide 25 is normally under the 70 influence of the spring 26 which acts upon the slide or cut-off to hold it in the position indicated in, Fig. 4, whereby it prevents movement of rivets downward in the chute. Pivoted to the block 5 at 27 is a slide actuator 28, the upper end 29 of which is in the path of a pin 30 mounted on the actuating arm 15. The actuator 28 is provided with a leaf spring 31, the end of which normally rests against the end of the slide or cut-off 80 25 opposite the spring 26, the construction being such that upon operative movement being imparted to the arm 15 as hereinbefore explained, the actuator 28 will be moved upon its pivot 27 and the leaf spring 31 85 thereof will cause a yielding movement of the slide 25 to bring the opening of the slide in position to permit a rivet in the chute to pass to the lower part thereof, as usual.

From the construction thus far described, it will be noted that by the simple removal of the two screws 6 or other holding means, the block 5 together with its contained or supported rivet setting mechanism may be 90 entirely removed from the machine after having also removed the removable pin 14 which holds the ratchet operating arm to the actuating arm 15. It will also be noted that the slide 25 is moved in opposite directions by springs 26 and 31, the spring 31 being stiffer or more energetic than the spring 26 so that as the slide 25 moves to permit a rivet to pass down the chute to the holder, its actuation is of a yielding nature and likewise on its return so that in case of any obstruction, the slide or other parts may not be injured or broken.

As hereinbefore pointed out, different kinds of work require different kinds of work supporting posts or spindles, and it is a recognized fact in the art that the spindles must be retained with sufficient rigidity to withstand the repeated blows delivered thereto by the rivet setting mechanism. This rigidity is most fully secured by a short work supporting post or spindle on account of the shorter leverage, and the art has recognized this fact by the employment of such short posts or spindles where the character of the work to be done permitted. The rigidity of the work-supporting spindle is also dependent upon its rigid connection with the supporting part which, in the ordinary riveting machine, is part of the machine frame.

In order that the rivet setting may be carried into effect upon the bottom portion of deep hand bags, trunks, and the like, a long supporting post or spindle is required;

but where more shallow receptacles such as suit cases, and the like are to be riveted, a somewhat shorter spindle may be employed; and where hinges, locks, and the like are to be riveted to the hand bag or other receptacle, a short spindle or stud is found suitable. These various contingencies have required the ordinary factory equipment to employ three machines, because the life of any machine is dependent to a large extent upon the length of the spindle employed, and greater facility in handling and performing the work is afforded by shorter spindles. The present invention, therefore, contemplates providing a single rivet setting machine with a plurality of work supporting spindles or posts of varying lengths as required by the different kinds of work to be done, and so mounting and supporting such posts or spindles that they shall all be rigidly held in operative position and may be brought into operative position as required and then locked in such position. As a good form of means to this end, the invention illustrated herein comprises a sleeve 32 which has extended bearings upon the spindle 2 as on the enlarged parts 33 thereof. These bearings 33 are separated to support and impart stability to the sleeve 32 while permitting rotative movement thereof, and such stability of the sleeve may be enhanced, at times, if desired, by having the sleeve split and provided with set screws or bolts 34 whereby the sleeve may be firmly clamped upon the bearings 33. The rigidity of the work supports when brought into operative relation with the riveting machines will determine to a large extent the character and accuracy of the work performed by said mechanism and the present invention, in recognition of this fact, seeks to so mount the rotatable sleeve 32 upon the machine column as to impart thereto the desired rigidity.

The sleeve 32 has flattened lugs 35 formed thereon at different heights and to each of these flattened lugs is rigidly bolted the work supporting spindle brackets 36, 37 and 38. These supporting brackets may be secured to the sleeve 32 by any appropriate means and as shown, they are secured thereto by means of bolts 39.

Referring to Fig. 1, it will be noted that the rivet setting mechanism is supported above the machine column 2 at one side of the axial center thereof by the goose-neck 3 and the work post supporting brackets 36, 37, 38 are therefore made of sufficient length to position the various work supporting posts or spindles in proper relation to the rivet setting mechanism.

For setting rivets in deep bags or the like, there is provided on the arm 38 a work supporting post or spindle 40, the upper end 41 of which may be of appropriate work supporting structure. This post or spindle

may be secured to the bracket 38 by a suitable nut 42. Similarly, the post 43 for supporting more shallow hand bags and the like for the rivet setting operation may be appropriately carried by its bracket 37 and secured thereto by a nut or other means 44. The shortest of the work supporting spindles or posts is carried by the bracket 36 as indicated at 45 and may be secured to the bracket 36 in appropriate manner by the nut 46.

From the construction thus far described, it will be apparent that the sleeve 32 is rotatably mounted upon the machine column by the extended bearings 33 and that the work supporting posts or spindles 40, 43 and 45, which are progressively of less longitudinal extent, are supported respectively along different portions of the sleeve, according to the length of the work supporting posts or spindles.

In order to hold the sleeve 32 in proper locked position when one of the work supporting posts or spindles is brought into operative relation with the riveting mechanism, suitable means are provided. In the present form of the invention, such means consists of a series of separated lugs 47 secured to the lower part of the sleeve 32, preferably in axial alinement with the respective work supporting posts or spindles, and mounted upon lugs 48 on the machine column 2 is the latch 49, one end of which is adapted to normally engage between the lugs 47 on the sleeve under the dictates of a suitable spring as 50 which acts upon the tail-piece 51 of the latch, the construction being such that by pressing upon the tail-piece of the latch as by the foot, the sleeve may be freed to rotative movement within the amplitude as will presently be described; and when the desired spindle or post has been brought into operative relation with the riveting mechanism, the latch may be freed to positively lock the parts in the new relation.

Pivotedly mounted at 52 near the base of the machine column is the treadle 53, the rearwardly extending arm 54 of which has pivotally connected to it at 55 a link 56, the upper end of which is joined to the actuating arm of the rivet setting mechanism as at 57, the construction being such that upon depression of the treadle 53 against the tensions of the spring 58 as indicated in Fig. 1, the rivet setting mechanism may be operated, as will be fully understood by those skilled in the art. It will be noted that the connections between the treadle 53 and the actuating arm of the rivet setting mechanism extend upward from the base portion of the machine and as indicated in Fig. 3, would interfere with the free rotation of the sleeve 32 by reason of the bracket arms 36, 37, 38 which would contact with the said

connection. In the present invention, therefore, the several work supporting posts or spindles are connected to the sleeve 32 in an arc extending less than 180° about said sleeve, as indicated in Fig. 3, so that any one of the work supporting spindles or posts may be brought into operative relation with the rivet setting mechanism without interference by the connection between the treble and the means for actuating the rivet setting mechanism.

In order that the rotatable sleeve 32 may be properly sustained by the machine column, the latter is provided with a shouldered portion 59, Fig. 1, on which the lower end of the sleeve 32 rests. The upper portion of the sleeve will be held in place by the base portion of the goose-neck 3 secured to the machine column, the construction being such that when free to rotate, by disengagement of the latch 49, from the lug 47, the sleeve 32 may be turned about the machine column, as desired.

What is claimed is:—

- 25 1. In a rivet setting machine, the combination of a machine column, a rivet setting mechanism above said column, a sleeve inclosing said column and rotatably mounted about said column and provided at different points in its height with a plurality of independent work supporting posts or spindles of different lengths, and means for securing the sleeve in adjusted position with any one of the posts or spindles operatively related to the rivet setting mechanism.
- 30 2. In a rivet setting machine, the combination of a machine column, a rivet setting mechanism sustained by said column, means extending from the base portion and outside the machine column for operating the rivet setting mechanism, and a sleeve rotatably mounted on the machine column and having a plurality of work supporting posts or spindles of different lengths secured in different horizontal planes to said sleeve and arranged within an arc of less than 180° about said sleeve to permit the latter to be rotated sufficiently to bring any one of the posts or spindles into operative relation with the rivet setting mechanism.
- 35 3. In a rivet setting machine, the combination of rivet setting mechanism, a sleeve, a machine column having separated bearing portions on which said sleeve is mounted for rotative movement, a series of brackets rigidly secured to said sleeve at different longitudinal portions thereof, work supporting spindles of different lengths carried by said brackets, the length of said spindles varying inversely as the heights of the brackets to which they are respectively secured, and means for locking the sleeve in position with any one of the work supporting spindles operatively related to the rivet setting mechanism.

4. In a rivet setting machine, a machine column, rivet setting mechanism carried thereby, a rotatable sleeve mounted on the column and provided with bracket supporting portions at different heights thereon, brackets of uniform length rigidly secured to said supporting portions, a work supporting post or spindle carried by each bracket, the post or spindle carried by the lowermost bracket being of greater length than the other posts or spindles, and said other posts or spindles being progressively shorter as the height of the brackets to which they are attached increases, and means for locking the sleeve in position.

5. In a rivet setting machine, a machine column, rivet setting mechanism carried thereby, a rotatable sleeve mounted on the column and provided with bracket supporting portions at different heights thereon, brackets of uniform length rigidly secured to said supporting portions, a work supporting post or spindle carried by each bracket, the post or spindle carried by the lowermost bracket being of greater length than the other posts or spindles, and said other posts or spindles being progressively shorter as the height of the brackets to which they are attached increases, means for locking the sleeve in position, and means to clamp the sleeve tightly to said bearing portions to rigidly sustain the work supporting spindles during the action of the rivet setting mechanism.

6. In a rivet setting machine, the combination of a machine column, rivet setting mechanism supported in fixed position relative thereto, a horizontally rotatable sleeve mounted on the machine column and provided with bracket securing lugs at different heights thereof, work supporting brackets of uniform length rigidly secured to and projecting from said securing lugs, a work supporting spindle rigidly secured to each bracket, said spindles varying in length inversely as the height of the brackets to which they are secured, and means for rigidly clamping the sleeve to the machine column to rigidly sustain the sleeve and work supporting spindle during the rivet setting operation.

7. In a rivet setting machine, the combination of a machine column, rivet setting mechanism carried thereby, means extending from the base of and outside said column for operating the rivet setting mechanism, a sleeve mounted for rotative movement on said column, a series of brackets secured to and projecting from said sleeve in different horizontal planes, each bracket carrying a work supporting spindle differing in length from the other spindles, said brackets being arranged circumferentially of the sleeve at less than 180° to permit any one of the spindles to be brought into operative rela- 130

tion with the rivet setting mechanism, and means for securing the sleeve in adjusted position.

8. In a rivet setting machine, the combination of a machine column 2 having extended bearing portions 33, a sleeve 32 mounted to turn upon said bearing portions, a series of brackets extended from said sleeve at different longitudinal portions thereof, and work supporting spindles of varying lengths secured to said brackets, the length of the sleeve being greater than the length of the longest work supporting spindle to rigidly maintain any of the spindles in operative position.

9. In a riveting machine, the combination of a machine column, a rivet setting mechanism, a sleeve mounted on the machine

column for rotative movement about the longitudinal axis of said column, a series of brackets rigidly secured to the sleeve in different horizontal planes, and work supporting spindles carried thereon with their tops in the same horizontal plane, whereby the minimum working height may be given to each of said spindles and still preserve the proper vertical working distance between the top of a spindle and the rivet setting end of the rivet setting mechanism.

In testimony whereof, I have signed my name to this specification, in the presence of two subscribing witnesses.

JAMES W. COOMBS.
